CONVENIENCE OUTLET

Filed Dec. 22, 1926

UNITED STATES PATENT OFFICE

MARK N. RUSSELL, OF SYRACUSE, NEW YORK, ASSIGNOR TO PASS & SEYMOUR, INC.,
OF SYRACUSE, NEW YORK, A CORPORATION OF NEW YORK

CONVENIENCE OUTLET

Application filed December 22, 1926. Serial No. 156,475.

This invention relates to convenience outlets and more particularly to that type of convenience outlet mounted in the canopy of a light fixture.

5 It is a general object of the present invention to provide a novel and improved form of convenience outlet.

More particularly it is an object of this invention to provide a convenience outlet of a novel form adapted to be secured to the rear face of a canopy formed of insulating material.

Another object of the invention consists in the provision of a convenience outlet adapted 15 to be secured to the rear face of the canopy of a light fixture and having terminal screws for the service wires and attaching screws for the conductors leading to the lamp socket of the fixture.

20 A still further object of the invention consists in the provision of a compact convenience outlet for fixture canopies in which a pair of springs are adapted for cooperation with the blades of a parallel-bladed attachment plug, said springs having their greater length transverse to the length of the blades and being supported directly from terminal members.

Other and further objects of the invention 30 will be more apparent to those skilled in the art by a consideration of the accompanying drawing, taken together with the following specification, wherein is disclosed a single embodiment of the invention with the understanding, however, that various changes may 35 be made therein such as fall within the scope of the appended claims without departing from the spirit of the invention.

In said drawing:

40 Figure 1 is a rear elevation of a fixture showing the convenience outlet of the present invention secured to the canopy thereof;

Figure 2 is a transverse section on line 2—2 of Figure 1;

45 Figure 3 is a transverse section on line 3—3 of Figure 1;

Figure 4 is a front or face view of the convenience outlet removed from the canopy;

50 Figure 5 is a central vertical section on line 5—5 of Figure 4, and

Figure 6 is a perspective view of the convenience outlet.

Under certain conditions it is found highly desirable to provide the canopies of light fixtures with convenience outlets. By so doing a considerable amount of wiring is eliminated and the necessity of providing a convenience outlet at some other part of the room is overcome. These features are of particular value in such outlets as may be used in bathrooms, kitchens and the like where the walls are often tiled at least a portion of their height and difficulty is experienced in providing a convenience outlet thru the tile. A convenience outlet mounted in the canopy of a fixture is more readily accessible and is at a more convenient height than those usually arranged in the baseboard or near there.

In the copending application of Don. N. Thompson Serial No. 93,800, filed March 10, 1926, for lighting fixture is disclosed a form of all-porcelain lighting fixture to which it is preferred to attach the convenience outlet of the present invention. The drawings show the convenience outlet attached to such a fixture but it is to be understood that it may equally well be attached to various other types of fixtures having a canopy formed of insulating material or having an insert of insulating material in the canopy.

Referring to the drawing, it will be seen that the fixture comprises a canopy 10, elliptical in shape and adapted to be attached to an outlet box by means of an adapter such as 11. On the face of the canopy a bracket supports the socket 12 to receive a lamp, which socket is provided with a pull chain conveniently operated by a pendant 13 for turning the light on and off. Beneath the bracket, supporting the socket, the face of the canopy is substantially flat as shown at 14 and is provided with a pair of spaced rectangular slots 15 sized and located to receive the blades of the conventional parallel-bladed attachment plug. These slots 15 pass thru the canopy and into an irregularly shaped recess 16 in the rear face thereof. This recess communicates by way of the two slots or passages 17 with the large circular recess 18 in the back of the canopy provided to receive the

adjustable adapter 11. A suitable opening 19 leads from the recess 18 to the socket for the passage of wires such as 20 from the socket to terminals on the convenience outlet to be later described. Preferably the wires 20 pass beneath the adapter 11 and out thru a passage 21 and then to passages 17 and thence to the terminals.

The convenience outlet per se is a composite structure formed on the insulating base plate 22 which comprises, essentially, a central square portion 23 and the two wings 24. Attached to the base plate but spaced therefrom and of the same shape and substantially the same size is the cover plate 25. The spacer 26 of insulating material is arranged between the central portions of these two insulating plates 22 and 25. They are attached together by a hollow rivet 28 which passes thru the main or base plate 22, the spacer 26, the cover plate 25 and a metal reinforcing strip 29. This reinforcing strip has one end reduced and bent at right angles as shown at 30 and passing thru a hole 31 in the three insulating pieces. This bent end together with the rivet prevents any relative rotation of the three insulating members while the rivet serves to hold them together. A hole 32 passes centrally thru the insulating members and a smaller threaded hole 33 in alignment therewith thru the metal reinforcing member. This latter hole is adapted to receive the threaded end of a screw 34 which passes thru the canopy plate between the slots 15 and securely holds the outlet assembly in position with the inner face of the square portion 23 of the base plate securely against a central rib 35 projecting into the recess 16 in which the outlet is mounted. It will be seen that the screw draws the reinforcing metal plate 29 down against the insulating parts and assists in clamping them more tightly together. Rotation of the outlet assembly in respect to the canopy is prevented by the engagement of the edges of the plates 22 and 25 with the walls of the recess 16.

On the side of the main insulating plate 22 facing the front of the canopy are attached the two metal strips 36. These have flat wings 37 which lie along the extensions of the insulating plate and are attached thereto by the hollow rivets 38. Near the end of each of the wings 37 is arranged a terminal screw 39 threaded thru the wing and the insulating base plate and adapted to receive service wires which convey current to the convenience outlet and the lamp socket. Between these screws 39 and the hollow rivets are the smaller screws 40 similarly attached and adapted to receive the wires 20 leading to the lamp socket. By this means the lamp socket is put into permanent connection with the service wires. Suitable lugs 41 may be struck out from the wings 37 to assist in attaching the wires.

Each wing 37 has formed integral therewith the contact supporting plate 42. This plate is bent at right angles to the face of the insulating base plate and also extends at right angles to the axis of its wing 37, as clearly shown in Figure 6. These contact supporting plates are spaced from the insulating plate where they are not attached to the wings 37 as best shown in Figures 2 and 5. The contact supporting plates face each other across the central portion of the base plate and each carries on its inner face a contact spring 43. As best seen in Figures 4 and 6 these contact springs comprise strips of spring material of substantially the same length and width as the contact supporting plates 42. The middle portions of these contact springs are bowed, as shown at 44, so that only the ends contact with the supporting plates. The ends of the supporting plates remote from their attachment to the wings 37 are provided with means whereby the ends of the contact springs may be attached thereto. Conveniently, portions of the supporting plates are punched up to form rivets 45 to pass thru openings in the springs and secure them rigidly against the supporting plates. Similar rivets may be struck thru the opposite ends of the supporting plates but do not pass thru the contact springs. The inner ends of the springs have a rectangular portion removed from one corner so that the two right angled walls 46 engage this rivet. This prevents any great flattening of the spring or any movement about the rivet 45 in a direction toward the insulating base plate.

When the receptacle is mounted in the canopy the central bowed portions of the contact springs project into the paths of the plug blades when they pass thru the passages 15, as best shown in Figure 2, and the center of each bowed portion is provided with a struck-up projection 47 to be received in the usual indentation in the end of the plug blade to prevent the blade from jarring loose. It will be seen that this projection 47 is opposite the wall 48 of the passageway 15 and is so close thereto that the spring must be pushed aside by the blade in passing, thus insuring a tight contact. A projection 49 on each spring, facing in the direction of the openings of the recesses 15, is bent slightly to the side to insure correct passage of the blade over the front face of the spring. The main insulating plate 22 is perforated as at 50 in line with the recesses 15 to receive the ends of the plug blades in case they are of sufficient length.

In wiring a receptacle provided with the present form of convenience outlet the socket is first wired, the wires brought out thru the opening 19 and beneath the adapter and are attached to the screws 40 on the convenience outlet which has previously been removed from the canopy. The service wires are then attached to the convenience outlet by means

of the screws 39. The screw 34 is then inserted to secure the convenience outlet to the canopy and the canopy is then attached to the outlet box in the usual manner.

5 It will be seen that the particular arrangement of contact springs enables the provision of an extremely thin convenience outlet which can be thus arranged in a very shallow canopy. The blades of the attachment plug pass 10 by the springs and even beyond the surface on which they are mounted. The whole device is readily formed from punchings of insulating sheets and metal and the whole is secured together by five riveting operations. The 15 wings of the cover plate 25 are slightly wider than those of the main base plate so that when the device is in position the cover plate fills up the opening of the recess 16 with the exception of the entrance of the grooves 17 20 therein so that no live parts are exposed at the back of the canopy. The rib 35 passes between and effectively separates the contact springs so that there is no chance of arcing between the same. The main insulating plate 25 abuts the lower face of the rib and prevents arcing around this rib. Adequate protection 25 is thus given in every respect.

Having thus described the invention, what is claimed as new and desired to be secured 30 by Letters Patent is:

1. In a convenience outlet, in combination, a base of insulating material, a metal wing attached to one face thereof, a contact carrying portion integral with said wing and in a 35 plane at right angles thereto, a bowed contact spring having its ends in engagement with said portion, and means near the center of the outer edge of said spring to guide a plug blade over the bowed face of the spring and 40 away from said contact carrying portion.

2. A contact assembly including a conducting contact support having a substantially flat face, a bowed contact spring having its end portions against said face, one of said 45 end portions being secured to said face, and means on said face to guide the other end portion for movement along said face when the spring is flexed.

3. A contact including a substantially rectangular strip of metal having its center portion slightly bowed out of the plane of the ends, a guide lug extending from substantially the center of one of the long sides of the strip and being bent toward the plane of the 55 end portions.

4. A contact assembly including in combination, an L-shaped conductor strap, one leg thereof adapted to be secured to a base, a terminal on said leg, the other leg being in 60 a plane at right angles to said first leg and having a substantially flat face, a contact spring formed of a strap of spring material of substantially the size of the face, the end portions of said spring being in engagement 65 with said face and the center portion bowed

away therefrom, a guide lug extending from the bowed portion of said spring, means securing one end of said spring to said flat face, and means at the other end of said face to resist bending of said spring.

5. A convenience outlet assembly for a canopy, including in combination, an insulation base sheet having wings, a pair of contact carrying members, portions thereon attached to said wings, terminal screws passing through each portion and the base sheet, a contact support integral with each said portion and at right angles thereto and to the sheet, said supports facing each other, a contact spring on the facing side of each support, said spring engaging the support at its end portions and being bowed away at the middle portion, one end of said spring being secured to said support, a cover plate of insulating material, a spacer and a reinforcing member, said cover plate covering the ends of said screws and being spaced from said base sheet by said spacer and means to secure said base sheet, spacer, cover plate and reinforcing member together.

6. A contact assembly for convenience outlets including in combination, a conducting support having a substantially flat face, a contact spring extending along said face, engaging the same with face contact at the ends and bowed away at the center, means securing one end of said spring to said support and means on said support engaging the other end of said spring to prevent rotation about the fastening means when an engaging contact moves transversely of said spring.

In testimony whereof I hereunto affix my signature.
